CLAIM

The ornamental design for a combined belt buckle sleeve and cover, as shown and described.

DESCRIPTION

FIG. 1 is a rear perspective view of a combined belt buckle sleeve and cover showing my new design;

FIG. 2 is a front perspective view;

FIG. 3 is a top plan view;

FIG. 4 is a rear elevational view;

FIG. 5 is a bottom plan view;

FIG. 6 is a left side elevational view; and,

FIG. 7 is a right side elevational view.

The broken line showing of a belt in FIG. 1 is for illustrative purposes only and forms no part of the claimed design.
